UNITED STATES PATENT OFFICE

1,936,253

MATRIX-STICK

Philip P. Merrill, Evanston, Ill., assignor to
 Ludlow Typograph Company, Chicago, Ill., a
 corporation of Illinois

Application June 25, 1932. Serial No. 619,341.

2 Claims. (Cl. 199—47)

My invention relates to sticks for matrices such as are commonly employed in the casting of type-slugs bearing lines of printing characters, these sticks being provided for receiving and holding a number of detached matrices in selected relation, thereby forming a composite matrix apart from, but adapted to co-operate with, a mold when the stick is temporarily applied to operative position with relation thereto and produce the desired line of printing characters on the slug formed in the mold.

It is often desirable in the printing of matter occupying a plurality of lines, such as in column printing, that the printed matter at the ends of the several lines thereof be accurately vertically aligned in the printed composition, which requires that the matrices assembled in the stick, for each line of printing characters, present composite matrices of exactly the same length for the several lines of printing characters.

My object is to provide a matrix stick with indicator means, co-operating with the movable-quad-clamping screw thereof, whereby the several lines of matrices composed in succession in the stick, may be caused to be of exactly the same length as determined by the first-composed line for the purpose above stated.

Referring to the accompanying drawing:

Figure 1 is a broken plan view of a matrix-stick embodying my invention and showing it in position for casting in a slug-casting machine.

Figure 2 is a broken view in vertical sectional elevation of the stick and slug-casting machine, the section being taken at the irregular line 2 on Fig. 1 and viewed in the direction of the arrow.

Figure 3 is a face view of plural-line column printing illustrating the vertical alinement of the lines of printed characters at opposite ends of the lines and for the producing of which my present improvements have been devised; and

Figure 4, a broken, enlarged, sectional view taken at the line 4 on Fig. 1 and viewed in the direction of the arrow.

In accordance with common practice the matrix stick shown at 5 and embodying my invention as hereinafter described, co-operates with a mold-member 6 of a line-slug casting machine as commonly provided, presenting a mold cavity 7 in which the shank of the line-slug to be produced is cast, the metal to form the slug being projected upwardly into the mold-cavity through its open bottom and against the line of matrices in the stick, which latter is accurately positioned relative to the mold-cavity 7 by a stop 8 provided on the bed 9 of the machine and con-

taining an opening 10 into which the mold member 6 extends.

The matrix stick shown comprises a frame-like body portion 11 presenting an opening 12 in which the matrices 13 against which the metal 60 introduced into the mold cavity 7 is cast to form the slug-head line of printing characters on the slug, are positioned, one of the side bars of the frame 11 being provided with a scale 14 presenting graduations corresponding with the different lengths of slug-head lines to be produced.

The matrix stick also comprises a block 15 slideable in the opening 12 and forming the movable end quad of the stick, and by which the line of matrices is clamped against the stationary end-piece 16 of the frame 11.

The end quad 15 is operated by means of a screw shaft 17 rotatably mounted in the other stationary end piece 18 of the frame 11 in which it is held against lengthwise movement therein, 75 the threaded portion 19 of the shaft screwing in the threaded opening 20 in the end quad 15.

The shaft 17 is shown as provided with a flange 21 at which it bears against the inner face of the end-piece 18 and at the opposite face of the 80 end-piece 18 with a sleeve 22 pinned thereto at 23 and presenting a flange 24, a knurled knob 19^a by which the shaft 17 may be readily operated being attached to the outer end of the sleeve 22 in spaced relation to the flange 24, the construction just described serving to adapt the shaft for rotation in the end piece 18 but restraining it against lengthwise movement therein.

In accordance with my invention I provide means angularly positionable about the shaft 17 90 and serving as an indicator for the operator in spacing, or justifying, in succession, the lines of matrices in the stick, these means in the particular construction shown comprising a sleeve 25 surrounding the shaft 17 and sleeve 22 and angularly adjustable about the longitudinal axis of these parts. The sleeve 25, which is preferably knurled as represented at 26, is provided with an inwardly extending annular flange 27 spaced 100 from the flange 24. Surrounding the sleeve 22 and located between the flanges 24 and 27 is a coil spring 28 which yieldingly forces the sleeve 25 at its flange 27 against the opposing face of the knob 19^a to frictionally grip the sleeve 25 to 105 the knob 19^a and thus to the shaft 17 to cause the sleeve 25 to rotate with the shaft but permit it to be rotated by the operator about the shaft into different angular positions thereon, the sleeve 25 having a line-marking 29 co-operating 110

with a line-marking 30 on the adjacent end piece of the frame 11 and forming indexing means.

In the use of the matrix stick for composing lines of matrices in succession, the operator assembles in the opening 12 of the stick, the line of matrices 13 and spaces 31 for the casting of the printing characters of the first slug of the plural line-slug composition, having regard to the length of the slug-head line, or measure, to be produced. The scale 14 serves as a guide in this connection and in the particular example illustrated the slug-head line is to be of 22 pica measure so that the line of matrices justified, as for example, by the spaces 31, closely approximates registration with the 22 mark on scale 14 when the quad-screw 19 is tightened sufficiently to clamp the line of justified matrices in the stick against displacement therein in the handling of the stick, but without sufficient pressure to prevent relative floating of the stick and matrices in the assembling of the stick with the slug casting machine, into casting position. Following this clamping operation the sleeve 25 is rotated relative to the shaft 19 to a position in which the marking 29 exactly registers with the marking 30.

After producing the first line-slug referred to, the operator backs away the quad 15 by reversely rotating the shaft 19, to release the matrices and spaces in the stick for their removal and replacement by the matrices and spaces from which matrices the printing characters on the second line-slug to be cast for composition with the first line-slug, are produced. As the sleeve 25 rotates with the shaft 19 the positioning of the sleeve on the shaft to cause its marking 29 to register with the marking 30 in the clamped condition of the first line of justified matrices as above stated, is not disturbed, and the marking 29 serves as an accurate guide to the operator in justifying this second line of matrices to exactly the same measure as the first line of justified matrices, the operator spacing out, as by the spaces 31, the matrices to justify this second line to such an extent that when the quad 15 clamps the line of matrices and spaces with the desired force, as above explained, the marking 29 on the sleeve 25 will exactly register with the marking 30. As will be understood the lines of matrices

and spaces used in producing the others of the line-slugs to complete the composition are clamped, in succession, in the stick, the sleeve 25 remaining in the position to which it was rotated on the shaft 19 for the first line of matrices, throughout the assembling and spacing of all of the lines of matrices used in producing the slug-line composition. Thus all of the lines of printing produced by the impressions made by the several line-slugs cast from matrices as above stated will be accurately aligned at both ends of the lines of printing as shown in Fig. 3.

While I have illustrated and described a particular construction embodying my invention, I do not wish to be understood as intending to limit it thereto, as the same may be variously modified and altered without departing from the spirit of my invention.

What I claim as new, and desire to secure by Letters Patent, is:

1. A matrix stick comprising a frame portion to receive matrices and spaces, means for clamping the matrices and spaces in said frame and comprising a rotatable operating element, an outwardly extending projection on said element, a sleeve rotatable on said element, an inwardly extending projection on said sleeve, a spring between said element and sleeve and engaging said projections and pressing said sleeve into frictional engagement with said element, and indexing means comprising co-operating portions one of which is on said sleeve.

2. A matrix stick comprising a frame portion to receive matrices and spaces, a sliding block for clamping the matrices and spaces in said frame portion, a screw shaft journaled in said frame portion and held against longitudinal movement and having threaded engagement with said block, an outwardly extending projection on said screw shaft, a sleeve rotatable on said screw shaft, an inwardly extending projection on said sleeve, a spring between said screw shaft and sleeve and engaging said projections and pressing said sleeve into frictional engagement with said screw shaft, and indexing means comprising co-operating portions one of which is on said sleeve.

PHILIP P. MERRILL.
